UNITED STATES PATENT OFFICE.

ELMIRA CRAGG, OF CLEVELAND, OHIO.

WORK-HOLDER.

1,185,289.

Specification of Letters Patent. Patented May 30, 1916.

Application filed March 29, 1915. Serial No. 17,903.

To all whom it may concern:

Be it known that I, ELMIRA CRAGG, a citizen of the United States, residing at Cleveland, in the county of Cuyahoga and State of Ohio, have invented certain new and useful Improvements in Work-Holders, of which the following is a specification.

My invention relates to a work holder for seamstresses and others, and the object 10 of the invention is to provide a simple form of holder adapted to anchor a piece of goods temporarily while sewing or basting the goods, and which will permit quick and convenient attachment and detachment of the 15 goods without injury thereto, and which is also adjustable preferably to permit the operator to work to the best advantage under different conditions.

In the accompanying drawings, Figure 1 20 is a plan view of one form of the work holder, full size, and Fig. 2 is a side view thereof, partly in section. Fig. 3 is a front elevation of the device. Fig. 4 is a face view of one of the clamping plates for the needles, 25 and Fig. 5 is a rectangular form of said plate. Figs. 6 and 7 are plan and side views corresponding to Figs. 1 and 2 but of a slightly modified form of the invention.

The invention comprises a work holder 30 adapted to be detachably secured in an upright position on a sewing machine, table or other base 2 in front of and at the right hand of an operator engaged in sewing or basting a piece of goods. The work holder 35 is used to anchor the goods at a suitable elevation above the table near the edge thereof so that it may be stretched and held taut more or less by the left hand while the operator sews or works on the goods 40 with her right hand. Stretching of the goods diagonally across the lap of the operator is the most advantageous position for convenient working, but the exact angle for a straight pull on the goods varies according 45 to circumstances and the option of the operator.

Now, referring to Figs. 1 to 5, I show a work holder A comprising a clamping bracket 3 made of a rigid strip of metal 50 bent at right angles at one end to support a clamping screw 4, and of Z shape or form at its opposite and upper end to support a pair of round flat disks or plates 5 and 6 in superposed relations, one or both of said 55 disks having two or more parallel shallow grooves 7 in their opposed faces to receive

and hold two or more needles or sharp pins 8. The points of these needles or pins project more or less in the same direction beyond the edges of the disks, and the needles are immovably clamped in place in any set 60 relation when the central screw 9 is rotated. Screw 9 passes through the central apertures in both disks and has screw-threaded engagement with the horizontally - projected 65 arm or end 10 of the clamp, but the disks are free to revolve thereon, except when the screw is tightened. In this way, the disks may be rotated and clamped to place the needles in any desired radial position relatively to the clamp body, thereby affording 70 the proper position of the needles for advantageous engagement of the cloth therewith regardless of the exact placing and fixing of the clamp upon the table or support. The disks may be round as shown 75 in Fig. 4, or a rectangular plate 6' may be used as shown in Fig. 5. The Z shape of the bracket affords room for doubling or folding of the goods under the disks and 80 overhanging arm 10 while part thereof overlies the top disk and is in hooked engagement with the needles. Substantially, the same results are obtained by the modified 85 form of the invention shown in Figs. 6 and 7, wherein the clamp body 11 is a cast metal member with a round flat head 12 upon which a single flat square plate 14 is adapted to be rotatably seated and clamped by a central screw 15. In this form of the 90 device, the needles 8 occupy two bottom grooves 16 in plate 14 and are clamped against the stationary head 12 except when the screw is loosened slightly to permit rotation and setting of the plate and its 95 needles in a different radial position to facilitate working operations.

The disks 5, 6, 6', 14, may be made of relatively thin sheet metal possessing spring properties so as to yield under undue pull 100 and to avoid tearing of the goods. The upper end of bracket 3, Figs. 1 to 3, may also be made of spring metal for the same reasons as outlined above.

What I claim is:

1. A work holder as described comprising an upright support, a plurality of separate needles and clamping means engaging said needles and adapted to be horizontally rotated on said support.

2. A work-holder for seamstresses and others, comprising a support, separate

105

110

clamping plates on said support, a set of separate needles horizontally positioned between said plates and a screw through said plates engaged in said support and adapted to clamp said needles in place.

3. A work holder adapted to anchor a piece of goods comprising separate needles, an upright support having a horizontal top, a clamp for the needles and a screw through

the same and the top of said support whereby said needles are rotarily adjustable to different horizontal positions.

In testimony whereof I affix my signature in presence of two witnesses.

ELMIRA CRAGG.
